UNITED STATES PATENT OFFICE.

ELMER GLENN KINZIE, OF LOGANSPORT, INDIANA.

FLYING MACHINE.

Application filed October 18, 1926. Serial No. 142,344.

This invention relates to flying machines, and possesses kindred qualities with aeroplanes comprising propelled planes extended at the sides, and with like machines whereof the wings may be worked up and down for supporting, propelling and directing the apparatus. It may also be properly classed with heavier than air constructions of the so-called "glider" variety, wherein limited or no sufficient motor power is used.

The object of this invention is the production of a machine of the character stated having parts of special construction and arrangement which are believed to be of the least expensive or complicated design, and which are especially strong and not liable to get out of order.

Of the accompanying drawings forming a part of this application, Figure 1 represents a side view showing all the parts assembled.

Figure 2 is a front view.

Figure 3 is a top plan view.

Throughout the description and drawings the same number is used to refer to the same part.

Considering the drawings the frame 1 may be of any chosen construction, and is usually provided with the landing gear including the front wheels 2 and 3, and a rear wheel 4.

This invention comprises a pair of wings 5 extending at the sides of the frame 1, in the usual manner. As both wings 5 are operated in the same way and by like parts, a description of the construction and arrangement of the parts for one wing will answer for both wings. The wings 5 are not attached directly to the frame 1, but they are connected by the hinge members 6 with the top or horizontal portion 7 of a T-bar, 8, the vertical portion or leg of which is marked 9. The bar is pivotally connected at the upper part of the vertical leg 9 with the frame 1 by the pivot bolt 10. The lower end of the vertical leg 9 of the T-bar is connected on either side with the frame by the springs 11 and 12. Thus, the leg 9 is held in position elastically by those springs, and if moved from its position in either direction the leg will be returned by the springs into its normal vertical position. A guard 13 attached to the frame limits the swinging movement of the lower end of the leg 9 of the T-bar.

This invention is intended to be operated manually or by any desired motor means.

The parts illustrated in the drawings are designed to be operated by man power. The operating devices include two levers 14 and 15, in practice provided at their lower ends with stirrups 16 and 17 so that the legs as well as the arms may be used. Each lever has a connecting rod 18 pivotally attached thereto, and to an angular lever contrivance formed by the arms 19 and 20 on a suitable cross shaft 21. With the arm 20 there is pivotally connected an upwardly extending rod 22, and the upper end of the rod 22 is attached to the wing 5 near its front edge by means of a universal joint 23. It will be understood that the parts just described as applying to the wings are in duplicate, one set for each wing 5. Both sets of parts are shown in Figure 2. In addition to the operating members as stated, each wing is connected towards its rear edge by means of the springs 24 and 25 with the frame 1. The springs 24 and 25 are shown in Figure 2.

As illustrated in Figure 3, the top of the frame 1 from front to rear is covered with a concave sheet of aluminum or other light material between the wings, and this top acts as a supporting plane when the invention is in flight.

At the rear of the frame 1 is mounted a tail plane 26, operated by cords 27 and 28 and the hand lever 29 as shown in Figure 1. The tail plane may be of any selected size or form, and this invention is not limited to any special mechanism for its operation. The function of the tail plane is to raise or lower the rear of the frame and correspondingly to direct its descent or ascent.

In the operation of this invention, it is to be borne in mind that the springs 24 and 25 connecting the rear of the wings and the frame, are given such strength as to hold the wings substantially horizontal during the flight. Therefore, when the levers 14 and 15 are operated the wings are raised against the force of the springs, but with the effect of the air as the frame tends to descend, and the springs aid the drawing of the wings downwardly. It has been explained that the rods 22 act upon the wings 5 near their front edges, and a downward pull upon the rods will tilt the wings by reason of their support upon the pivoted T-bar 8. Thus, when being worked up and down the wings assume an inclined position from front to rear. Air is thus shed by

the wings and thrown by them downwardly and rearwardly, and the whole is propelled in a forward direction. It is believed to be clear that by operating one wing by itself, the machine may be turned to either side. When constructed for use as a "glider" the operating devices materially aid the length of time the invention will be sustained in the air, and the steering is most conveniently accomplished.

If desired there may be provided means by which the wings 5 may be adjusted upon the portion 7 of the T-bar 8 either towards the front or rear of the frame 1, giving more or less tilt or inclination of the wings during the operation.

This invention is not limited to any material, size or particular formation of the parts mentioned, which may be obviously varied in many ways within the purview of this invention.

Having now described this invention, and explained the mode of its operation, what I claim is:—

1. In a flying machine of the character described, the combination with a frame, of a T-bar having a vertical portion and a horizontal portion, the said bar being pivotally connected with the said frame, springs attached to the frame and to the lower end of the vertical portion of the T-bar to hold the same elastically in place, wings secured to the bar pivotally and in adjustable relation thereto, means for working the wings up and down, a tail plane mounted at the rear of the said frame, and means for actuating the tail plane.

2. In a flying machine of the character described, the combination with a frame, of a T-bar pivotally connected with the frame, springs attached to the frame and bar for holding the vertical leg of the bar elastically in position, means for limiting the movement of the said leg of the bar, wings secured pivotally and in adjustable relation to the top of the said T-bar, means for working the wings up and down, a tail plane mounted at the rear end of the said frame, and means for controlling the said tail plane.

3. In a flying machine of the character described, the combination with a frame, of

a T-bar having a vertical portion and a horizontal portion, the said bar being pivotally connected with the said frame, springs attached to the frame and to the vertical portion of the T-bar to hold the same elastically in place, wings secured pivotally to the said bar, springs connected with the said frame and with the wings for holding the wings substantially horizontally in flight, means for working the wings up and down against and with the force of the said springs, a tail plane mounted at the rear of the said frame, and means for operating the said tail plane.

4. In a flying machine of the character described, the combination with a frame, of a T-bar having a vertical portion and a horizontal portion, said bar being pivotally connected with the said frame, springs attached to the frame and to the vertical portion of the bar to hold the same elastically in place, the said plane having a cover attached to the said frame and forming a plane extending lengthwise with respect to the frame between the wings, springs connected with the frame and with the wings for holding the wings substantially horizontal in flight, means for tilting the said wings independently of each other, a tail plane mounted at the rear of the said frame, and means for actuating the said tail plane.

5. In a flying machine of the character described, the combination with a frame, of a T-bar having a vertical portion and a horizontal portion, said bar being pivotally connected with the said frame, springs attached to the frame and to the vertical portion of the T-bar to hold the bar elastically in place, wings secured pivotally to the said bar, springs connected with the said frame and with the rear portions of the wings for holding the wings substantially horizontally in flight, means for working the front portions of the wings up and down against and with the force of the said springs, the said working means being adapted to rock the said T-bar and incline the wings independently upwardly from front to rear as the said wings are worked whereby the whole is propelled in a forward direction.

In testimony whereof I affix my signature.

ELMER GLENN KINZIE.
